EXPULSION-TYPE EXCESS-VOLTAGE
PROTECTIVE TUBE

Otto Ackermann, Irwin, Pa., assignor to Westinghouse Electric & Manufacturing Company, East Pittsburgh, Pa., a corporation of Pennsylvania

Application September 30, 1939, Serial No. 297,337

7 Claims. (Cl. 175—30)

My invention relates to excess-voltage protective devices or lightning-arresters of the explosion-tube type, in which an excess-voltage discharge is produced on the inside of an insulating tube under conditions producing a blast of deionizing gases or particles which assist in extinguishing the resulting arc.

The principal object of my invention is to produce such a tube, which will embody a major improvement in the lightning protective characteristic, as well as a greatly increased range of power-follow current which can be interrupted after the lightning-discharge.

With the foregoing and other objects in view, my invention consists in the structures, parts, combinations and methods hereinafter described and claimed, and illustrated in the accompanying drawing, the single figure of which is a longitudinal sectional view through a protector tube built in accordance with my invention.

The illustrated tube consists of an insulating tube 1, which is preferably of fibre or other gas-evolving insulating material which has the property of giving off large volumes of gases or other deionizing particles in the presence of an electric arc. I provide two tubular conducting electrodes 2 and 3 which extend partway into the tube 1, from opposite ends thereof, said electrodes being normally insulated from each other. The electrode 2 is open, at its end, so as to vent the interior of the tube, while the electrode 3 is not only closed by an end-cap 4, but also closed by an inner fibre rod-like filler or plug 5, one end of which is tightly pressed into the electrode 3 and riveted in place therein. The thickness of the wall of the tubular electrode 3 thus causes the inwardly projecting end of the fibre plug 5 to be spaced from the bore of the insulating tube 1 by a long, narrow, annular discharge-space or gap which extends from the closed tubular electrode 3 substantially to the open tubular electrode 2.

Closely surrounding the central portion of the insulating tube 1 is a strong steel or other metal tube 7 which terminates short of each end of the tube 1, and which is insulated from both of the electrodes 2 and 3. The metal tube 7 is long enough to overlap a portion S of each of the electrodes 2 and 3, with the wall of the insulating tube 1 interposed in between.

An adequate external sparking-distance is provided between the respective ends of the metal tube 7 and the respective metal end-caps 4 and 8 of the tube, so that these external sparking-distances will not break down during the

operation of the device. As a result of this precaution, the tube has a preferential internal flashover or discharge path in the long, narrow, annular discharge-space 6 between the two electrodes 2 and 3 within the bore of the insulating tube 1. In order that said external sparking-distance may be as small as possible, thereby conserving the space required by the protector tube, as well as reducing its cost, I prefer to fill these external sparking-distances with a liquid or semi-liquid insulating material, such as oil or petrodatum jelly 9, which is confined by means of short insulating tubes 11, so that the respective ends of the metal tube 7 are substantially embedded in insulating material, thus increasing the break-down strength of the space surrounding these ends of the metal tube 7.

The purpose of the metal tube or cylinder 7 is threefold. In the first place, it reinforces the fibre tube 1 and prevents its bursting at any part which is under radial stress during the discharge-conditions.

In the second place, the metal tube 7, by reason of its overlapping with the electrodes 2 and 3, produces a strong electrostatic coupling between the metal tube or shield 7 and each of the electrodes 2 and 3, each of these electrostatic couplings being of something like the same order of magnitude, and being considerably larger than the electrostatic coupling between the shield 7 and any reasonably spaced extraneous object, such as a grounded portion of the supporting-tower (not shown), whereby a material proportion of the total inter-electrode potential-difference is impressed at each of said electrostatic couplings between the shield 7 and the respective electrodes 2 and 3. If the overlapping distance S, is the same for each of the respective electrodes, and if the intervening wall-thickness of the insulating tube 1 is the same for each of these overlapping portions S, the two aforesaid electrostatic couplings will be identical, so that exactly half of the voltage-distance will appear at each coupling, assuming that the shield-to-ground capacitance is relatively negligibly small. In other words, the metal tube or shield 7 will always have a potential approximately midway between the potentials of the two insulated electrodes 2 and 3, whether they are discharging or not. This shielding-arrangement is thus distinctive in being substantially independent of the capacity of the shield to ground, which was considered to be of essential importance in previous shielding-arrangements which have been utilized on explosion-type tubes heretofore.

A third purpose of the metal tube or cylinder 7 is to concentrate the total available discharge-voltage near the inner ends of the respective electrodes 2 and 3, which constitute the terminals of the spark-gap or discharge between the two electrodes within the tube 1. Since the electrostatic couplings between the metal cylinder or shield 7 and the respective electrodes 2 and 3 are substantially equal, or at least of the same order of magnitude, a half, or some other substantial part, of the excess-voltage surge appears across the thickness of the fibre tube 1 at the inner end of each of the electrodes 2 and 3, thus creating a strong electrostatic stress at the arcing-tips of the respective electrodes 2 and 3, thus 15 greatly facilitating the initiation of ionization at these inner electrode-tips. Because of the dielectric strength of the fibre tube 1, this ionization does not produce a discharge or breakdown through the wall of the fibre tube, from the electrode to the shield 7, but it creeps along the inner bore of the fibre tube 1 and causes an internal breakdown between the inner ends of the two electrodes 2 and 3, so that this internal 20 discharge or breakdown or flashover starts at a much lower potential or voltage than would be the case if the shield 7 had not been provided.

It is also preferable that the wall or thickness of the fibre insulating tube 1 should be as thin as possible, so as to obtain the highest possible 30 potential-gradients and the closest electrostatic coupling at the respective electrode-tips, and so as to make the insulating tube 1 have a mechanical stress-distribution which is as uniform as possible, so as to transmit practically all of the internal bursting-pressure from the fibre tube 1 to the steel cylinder 7.

In order to assist in the provision of the aforesaid uniform stress-distribution, and in the transfer of the bursting stresses to the steel cylinder, it is also desirable that, for a given wall thickness, the insulating tube 1 should be of as large a diameter as feasible, so as to have a small ratio of outer diameter divided by inner diameter, because, then, the fibre wall, acting more or less like a lining on the inside of a steel tube, will be under radial compression rather than peripheral tension-stress. A small-bore fibre tube 1, with the same wall-thickness, would not so readily transfer its bursting stresses to the outer metal tube 7. It is thus desirable to have the inner bore of the fibre tube 1 so large that it would not provide a sufficiently narrow or restricted slot, discharge-space or channel between the two electrodes 2 and 3 if it were not for the provision of an insulating filler of some kind, such as the plug 5, between the electrodes, for providing a slotted passage or passages, of sufficiently restricted width, between the inner ends of the respective electrodes 2 and 3.

When I state that the wall of the fibre insulating tube 1 should be as thin as possible, I mean that said wall should have the minimum thickness necessary to provide the dielectric puncture-strength required to withstand half of the flashover discharge-voltage of the protective tube, with a reasonable factor of safety. In practical designs, it is frequently desirable to provide a sufficient factor of safety so that the puncture-strength of the fibre wall, between the metal tube 7 and either one of the electrodes 2 or 3, shall be equal to something like from 1 to 1.5 times the internal flashover voltage between the two electrodes 2 and 3, although I am not altogether limited to this range.

It will be typical, with my new type of protector, that the wall-thickness of the fibre tube 1 will increase with the voltage-rating of the tube. In order to avoid the utilization of insulating fibre tubes having thick walls, such as 5 would reduce the electrostatic coupling and the voltage-stress at the arcing-tips of the respective electrodes 2 and 3, it might be desirable, in the protection of lines or apparatus having 10 very high voltages, to connect two or more of my tubes in series. The close electrostatic couplings between my shield 7 and the respective electrodes 2 and 3 serve as a voltage-dividing means, so that not only each tube, but each electrode of each tube, gets its own proper share, or divided part, of the total overall voltage. I 15 can thus construct my improved protector tubes for a reasonable voltage of some low or intermediate value or values, and I may utilize a plurality of tubes connected in series with each other for the higher voltage-ratings.

While I have described and illustrated my invention in a single illustrative form of embodiment, which is at present preferred by me, I desire it to be understood that such description and illustration are to be understood in an illustrating sense rather than a limiting sense, at least insofar as the broader principles of my invention are concerned, as I realize that many changes, by way of additions, omissions, alterations, and substitutions may be made by those skilled in the art without altogether departing from some of the broader aspects of my invention. I desire, therefore, that the appended claims shall be accorded the broadest construction consistent with their language and the prior art.

I claim as my invention:

1. An expulsion-type excess-voltage protective tube comprising a thin-walled insulating tube, a conducting electrode extending partway into the tube at each end thereof, said electrodes being normally insulated from each other, at least one of the aforesaid parts being provided with venting means, a conducting strengthening-tube insulated from both electrodes and surrounding the central portion of said insulating tube to augment the bursting-strength of the latter, said conducting strengthening-tube terminating short 40 of both ends of the insulating tube and overlapping a predetermined portion of each of the electrodes, with the wall of the insulating tube interposed in between, said predetermined overlapping portion being of substantially the same 45 distance for each electrode, at least said interposed wall-portions of the insulating tube being of substantially the same thickness for each electrode, which thickness is substantially the minimum thickness necessary to provide the dielectric 50 puncture-strength required to withstand half of the flashover discharge-voltage of the protective tube, with a reasonable factor of safety, the inner bore of the insulating tube being larger than is 55 desirable for extinguishing the internal arc between the inner ends of the electrodes, and an inner plug of insulating material partly filling the bore of the insulating tube between the electrodes so as to provide a restricted-width slotted 60 passage or passages between the inner ends of the electrodes, the wall-material of said slotted 65 passage or passages including gas-evolving arc-responsive material, and the construction being such that a flashover always occurs internally 70 within the insulating tube between the inner 75 ends of the electrodes.

2. An expulsion-type excess-voltage protective tube comprising an insulating tube, a conducting electrode extending partway into the tube at each end thereof, said electrodes being normally insulated from each other, at least one of the aforesaid parts being provided with venting means, a tubular shield insulated from both electrodes and surrounding the central portion of said insulating tube and terminating short of both ends of the insulating tube and overlapping a predetermined portion of each of the electrodes, with the wall of the insulating tube interposed in between, said predetermined overlapping portion being of substantially the same distance for each electrode, at least said interposed wall-portions of the insulating tube being of substantially the same thickness for each electrode, the construction being such as to provide a restricted-width slotted passage or passages between the inner ends of the electrodes, the wall-material of said slotted passage or passages including gas-evolving arc-responsive material, and the construction being such that a flashover always occurs internally within the insulating tube between the inner ends of the electrodes.

3. An expulsion-type excess-voltage protective tube comprising an insulating tube, a conducting electrode extending partway into the tube at each end thereof, said electrodes being normally insulated from each other, at least one of the aforesaid parts being provided with venting means, a conducting strengthening-tube insulated from both electrodes and surrounding the central portion of said insulating tube to augment the bursting-strength of the latter, said conducting strengthening-tube terminating short of both ends of the insulating tube and overlapping a predetermined portion of each of the electrodes, with the wall of the insulating tube interposed in between, said predetermined overlapping portion being of substantially the same distance for each electrode, at least said interposed wall-portions of the insulating tube being of substantially the same thickness for each electrode, which thickness is substantially the minimum thickness necessary to provide the dielectric puncture-strength required to withstand half of the flashover discharge-voltage of the protective tube, with a reasonable factor of safety, the construction being such as to provide a restricted-width slotted passage or passages between the inner ends of the electrodes, the wall-material of said slotted passage or passages including gas-evolving arc-responsive material, and the construction being such that a flashover always occurs internally within the insulating tube between the inner ends of the electrodes.

4. An expulsion-type excess-voltage protective tube comprising an insulating tube, a conducting electrode extending partway into the tube at each end thereof, said electrodes being normally insulated from each other, at least one of the aforesaid parts being provided with venting means, a conducting strengthening-tube insulated from both electrodes and surrounding the central portion of said insulating tube to augment the bursting-strength of the latter, said conducting strengthening-tube terminating short of both ends of the insulating tube and overlapping a predetermined portion of each of the electrodes, with the wall of the insulating tube interposed in between, said predetermined overlapping por-

tion being of substantially the same distance for each electrode, at least said interposed wall-portions of the insulating tube being of substantially the same thickness for each electrode, which thickness is substantially the minimum thickness necessary to provide the dielectric puncture-strength required to withstand half of the flashover discharge-voltage of the protective tube, with a reasonable factor of safety, the inner bore of the insulating tube being the same for the two interposed portions between the conducting strengthening-tube and the inner ends of the respective electrodes and being larger than is desirable for extinguishing the internal arc between the inner ends of the electrodes, and an insulating filler between the electrodes for providing a restricted-width slotted passage or passages between the inner ends of the electrodes, the wall-material of said slotted passage or passages including gas-evolving arc-responsive material, and the construction being such that a flashover always occurs internally within the insulating tube between the inner ends of the electrodes.

5. An expulsion-type excess-voltage protective tube comprising an insulating tube, a conducting electrode extending partway into the tube at each end thereof, said electrodes being normally insulated from each other, at least one of the aforesaid parts being provided with venting means, a tubular shield insulated from both electrodes and surrounding the central portion of said insulating tube and terminating short of both ends of the insulating tube and overlapping a predetermined portion of each of the electrodes, with the wall of the insulating tube interposed in between, the electrostatic coupling between the shield and each electrode being of something like the same order of magnitude, and considerably larger than the electrostatic coupling between the shield and any reasonably spaced extraneous object so that the potential of the shield is substantially altogether determined by the potentials of the electrodes independently of the position of the protective tube with respect to any extraneous object, whereby a predetermined material proportion of the total interelectrode potential-difference is impressed at each of said electrostatic couplings between the shield and the respective electrodes, the construction being such as to provide a restricted-width slotted passage or passages between the inner ends of the electrodes, the wall-material of said slotted passage or passages including gas-evolving arc-responsive material, and the construction being such that a flashover always occurs internally within the insulating tube between the inner ends of the electrodes.

6. The invention as specified in claim 1, characterized by each of said electrodes being tubular, one of said tubular electrodes being open, and said inner insulating plug being secured within the other tubular electrode so as to provide an annular discharge-space for the discharge between the inner ends of the electrodes.

7. The invention as specified in claim 5, characterized by means for embedding the respective ends of the tubular shield in insulating material as an aid to preventing an external breakdown or flashover of the protective tube.

OTTO ACKERMANN.
